Patented Nov. 26, 1968

212,800

POWERED CASTER FOR TRAILERS AND THE LIKE

Howard M. Kimball, 3209 Hoyt Ave.,
El Monte, Calif. 91733

Filed Feb. 19, 1968, Ser. No. 10,626

Term of patent 14 years

(Cl. D14—3)

FIGURE 1 is a side elevational view of a powered caster for trailers and the like, showing my new design;
FIGURE 2 is a front elevational view thereof;
FIGURE 3 is a side elevational view showing the side opposite the side shown in FIGURE 1;
FIGURE 4 is a rear view thereof; and
FIGURE 5 is a top view thereof.

I claim:

The ornamental design for a powered caster for trailers and the like, as shown.
